UNITED STATES PATENT OFFICE.

EDWARDS R. FISH, OF WEBSTER GROVES, MISSOURI.

BOILER-FURNACE.

1,228,102.

Specification of Letters Patent. Patented May 29, 1917.

Application filed September 25, 1916. Serial No. 122,096.

To all whom it may concern:

Be it known that I, EDWARDS R. FISH, a citizen of the United States, residing at Webster Groves, Missouri, have invented a certain new and useful Improvement in Boiler-Furnaces, of which the following is a full, clear, and exact description, such as will enable others skilled in the art to which it appertains to make and use the same.

This invention relates to furnaces of the type that are used in connection with steam boilers.

Prior to my invention it was the usual practice, whenever a superheater was used with a steam boiler, to either arrange the superheater in such a position that it was subjected to the action of practically all of the furnace gases, or arrange the superheater in a chamber at the top of the boiler setting, which chamber was connected with the fire box or gas duct of the furnace by a flue or flues formed in a side wall of the furnace. If the superheater is subjected to the action of practically all of the furnace gases it is impossible to accurately control the degree of superheat, and if the superheater is arranged at the top of the boiler setting, the full efficiency of the gases used to heat the superheater is not utilized. Furthermore, considerable is added to the cost of building the furnace if a flue or flues are formed in the side wall of the furnace to conduct the gases to the superheater chamber.

One object of my invention is to provide a boiler furnace which is so designed that a superheater can be used with the boiler without the necessity of constructing a flue or flues in the side wall of the furnace or changing the boiler setting, thereby reducing the cost of building the furnace and also enabling a superheater to be added with very little trouble after the boiler has been installed.

Another object is to provide a boiler furnace which is equipped with a superheater arranged in such a manner that the degree of superheat can be accurately controlled and practically the full efficiency of the gases supplied to the superheater utilized.

To this end I have devised a boiler furnace provided with a superheater chamber arranged behind the bridge wall of the furnace in the combustion, ash or dust chamber; that is, the chamber, or space between the bridge wall and the rear wall of the furnace, said chamber being connected with the fire

box or gas duct of the furnace by a port or ports formed in said bridge wall and being provided with a damper controlled port or ports through which the gases can escape from said chamber, and thereafter flow over a part of the boiler in which steam is generated. My invention is applicable to furnaces for fire tube boilers and water tube boilers equipped with either vertical or horizontal baffles and heated by gas, liquid or solid fuel.

Figure 1 of the drawings is a vertical longitudinal sectional view of a water tube boiler provided with a furnace constructed in accordance with my invention and equipped with vertically-disposed baffles, the furnace being heated by waste gases; and

Fig. 2 is a similar view, illustrating a furnace constructed in accordance with my invention, used with a boiler provided with horizontally-disposed baffles, and heated by coal or solid fuel.

Referring to the drawings which illustrate the preferred form of my invention, A designates the drum, and B designates the tubes of a water tube boiler, said drum and water tubes being arranged in a substantially horizontal position over a furnace that is provided with either a gas duct C, as shown in Fig. 1, in which waste gases are supplied, or a fire box C', as shown in Fig. 2, in which coal or other solid fuel is burnt. The furnace is provided with a bridge wall D that separates the combustion, ash or dust chamber E from the gas duct C or the fire box C', and baffles F are provided for causing the furnace gases to flow in a tortuous passage over the tubes of the boiler in traveling to the flue G that leads to the stack (not shown), the baffles of the boiler shown in Fig. 1 being arranged vertically, and those of the boiler shown in Fig. 2 being arranged horizontally.

A superheater H, of any preferred design, is connected with the drum A by a conduit 1, or in any other suitable manner, so that the steam generated in the boiler will pass through the superheater H before it reaches the point where it is utilized. Said superheater H is arranged in the chamber or space E between the rear wall of the furnace and the bridge wall D and one or more ports 2 are formed in said bridge wall so that some of the furnace gases can pass directly from the gas duct C or fire box C' and act on the superheater H. The superheater is preferably arranged in a chamber

I, and the top wall of said chamber I is provided with one or more ports 3 through which the furnace gases can escape from the chamber I after acting on the superheater and flow upwardly over the tubes of the boiler to the flue G that leads to the stack. Various means may be used for controlling the supply of furnace gases to the superheater chamber, but I prefer to govern the outlet port or ports 3 of the superheater chamber by a damper or dampers 4 that can be regulated either manually or by an automatic temperature controller (not shown). When the damper or dampers 4 are open, as shown in the drawings, some of the furnace gases will be drawn into the superheater chamber I by the suction created in said chamber by the stack draft, thereby causing the superheater to be acted upon by the furnace gases when said gases are most efficient. After acting on the superheater, the gases escape from the superheater chamber I and flow upwardly over the tubes B of the boiler, thereby causing the remaining 25 available heat units in the gases to be utilized.

By arranging the superheater in a chamber located in the combustion, ash or dust chamber, behind the bridge wall, and providing means whereby any desired quantity of gases may be taken from the fire box or gas duct of the furnace, circulated through the superheater chamber and then allowed to escape from said chamber, I am able to accurately control the degree of superheat. Furthermore, as the gases used to heat the

superheater pass directly into the superheater chamber from the fire box or gas duct, and after acting on the superheater, flow over the tubes of the boiler in escaping to the stack flue, greater efficiency in the operation of the furnace is attained. Such a furnace can be built at a lower cost than a furnace having flues in its side wall, and still another desirable feature of such a furnace is that it makes it possible to combine a superheater with the boiler at any time without reconstructing the furnace.

Having thus described my invention, what I claim, and desire to secure by Letters Patent, is:

A boiler furnace provided with a superheater chamber, a superheater arranged in said chamber, a bridge wall which separates said chamber from the fire box of the furnace, said bridge wall being provided with an opening which establishes communication between said chamber and fire box, a partition wall which separates said superheater chamber from the combustion chamber of the furnace, and a valve in said wall which regulates the quantity of hot gases which enter said superheater chamber through the opening in the bridge wall and which also permits the gases which have been utilized to heat the superheater to thereafter pass into the combustion chamber and be further utilized to heat the tubes of the boiler, said valve being arranged adjacent the rear end of said superheater chamber.
